D. J. RADDICK.

OIL BURNER.

APPLICATION FILED AUG. 22, 1912.

1,097,188.

Patented May 19, 1914

UNITED STATES PATENT OFFICE.

DAVID J. RADDICK, OF NORDHOFF, CALIFORNIA.

OIL-BURNER.

1,097,188.

Specification of Letters Patent. Patented May 19, 1914.

Application filed August 22, 1912. Serial No. 716,520.

To all whom it may concern:

Be it known that I, DAVID J. RADDICK, a citizen of the United States, residing at Nordhoff, in the county of Ventura and State of California, have invented new and useful Improvements in Oil-Burners, of which the following is a specification.

My invention relates to oil burners.

One object of my invention is to provide a burner device of this type which will be free from the formation of soot, and one which will give a blue flame.

A further object of the invention is to generally improve the construction of a burner device of this kind.

The preferred embodiment of my invention is hereinafter described and illustrated in the accompanying drawings.

In said drawings:—Figure 1 is an elevation showing the burner body in section, and, Fig. 2 is a detail sectional view illustrating the burner.

Referring to the drawings, 1 designates an oil or fuel tank to which is connected a 25 hose or pipe 2, preferably flexible, leading from a hand operated pump 3. A pipe 4 or other suitable supply means, leads from the tank 1 to a retort pipe 5, which is deflected downwardly at 6 and returns at 7, 30 the end of which portion 7 is suitably deflected and provided with a burner proper 8. A suitable control or regulating valve 9 may be provided either in the pipe 4 or 5. The burner proper 8 preferably consists of 35 a hollow body, as shown in Fig. 2, having an extension thereon provided with screw threads to removably engage the end of the pipe portion 7. Said burner is also provided with a nozzle or outlet 10, the opening in 40 which has a tapered wall. A needle valve stem 11 is screw threaded in a projection 12 of the burner body and has a tapered point adjacent the opening in the nozzle 10. Said stem 11 is preferably provided with a 45 handle such as 13. In the bottom or other suitable portion of the burner proper 8 is provided a removable plug 14 preferably having a screw threaded shank 15 secured in an opening in the body.

The numeral 16 designates a burner casing, preferably cylindrical, perforated at the upper portion thereof, as shown. Said casing is suitably supported upon a base such as 17 as by means of arms 18 rising from the base and partly surrounding the casing. The pipe portions 5, 6 and 7, and the burner

8 are located within the casing 16 which has an open end through which said parts freely pass. In the bottom of the casing is provided a slideable flame deflector or spreader such as 19 which is arranged in alinement with and opposite the nozzle of the burner proper. The base 17 to which the casing is attached, preferably merely rests upon a support, so that the same can be readily disengaged or moved out of operative relation with the remainder of the apparatus to facilitate cleaning of the parts.

The fuel from the tank 1 is supplied under pressure obtained through the operation of 70 pump 3, through pipe 4, into pipe portions 5, 6 and 7 and through the nozzle 10, whose extent of opening may be regulated through the adjustment of the valve stem 11. The flame from the nozzle strikes against the 75 spreader 19 which causes the flame to spread and be deflected upwardly. The heat from the flame within the chamber acts on the pipes 5, 6 and 7, and the contained fuel under pressure therein and converts the 80 same into a gas so that the fuel emerges from the burner in a gaseous state. By means of the casing 16 being hollow together with the flame spreader means, the 85 heat is distributed evenly over the upper or perforated portion of the casing 16.

By means of the adjustable valve stem 11 the same may be adjusted to clean or remove soot or carbon from the opening in the nozzle 10, should such a deposit form therein. Also by means of the removable plug 14, access may be had to the interior of the burner 8 to clean the same without necessitating the removal of the burner proper from the pipe portion 7.

Changes within the spirit and scope of the appended claims are reserved.

Having thus described my invention, what I claim is:—

1. In a burner device, in combination with 100 a source of fuel supply, a pipe for the fuel having a burner thereon, a casing into which said burner extends having a wall arranged over the burner and having a flame deflector exterior thereof, said pipe extending in advance of and above said burner and flame deflector into said casing, said burner located at one side of said deflector to discharge its flame against the deflector for deflection upwardly against said pipe. 105

2. In a burner device, in combination with a source of fuel supply, a pipe for the fuel

having a burner thereon, a casing into which said burner extends having a perforated upper wall and having a flame deflector interior thereof, said burner located 5 at one side of said deflector, said deflector slidable longitudinally of the casing to and from said burner.

3. In a portable burner device, in combination with a source of fuel supply, a pipe 10 for the fuel having a burner thereon, a casing into which said burner extends mounted slidably longitudinally relatively to said pipe, said casing having a perforated upper wall extending over said burner.

15 4. In a portable burner device, in combination with a source of fuel supply, a pipe for the fuel having a burner member thereon, a casing member into which said burner extends having a flame deflector therein, one 20 of said members slidable relatively to the other whereby the parts may be adjusted to vary the distance between the burner and deflector.

25 5. In a burner device, pipe means to supply fuel comprising a main pipe portion, a

portion deflected downwardly therefrom into a return pipe portion located below the main pipe portion, a burner on said return pipe portion arranged to produce the flame beneath both of said pipe portions in a direction longitudinally of the pipe portions and toward the deflection of the main pipe portion, and a casing in which said pipe portions are located. 30

6. In a burner device, a main pipe portion to supply fuel, a portion deflected therefrom, a return portion connected to the deflected portion, a burner secured on said return portion, said burner having a nozzle, an adjustable valve controlling the extent of 35 opening of the nozzle, a casing having an open end into which the pipe portions and burner extend, a flame deflector in said casing adjacent the nozzle, and said casing having a perforated upper portion. 40
